(57) **CLAIM**

The ornamental design for a portable electric circular saw, as shown and described.

DESCRIPTION

FIG. 1 is a top, front and right side perspective view of a portable electric circular saw in accordance with our new design;

FIG. 2 is a top, rear and left side perspective view of the portable electric circular saw in accordance with our new design;

FIG. 3 is a front elevational view of the portable electric circular saw in accordance with our new design;

FIG. 4 is a rear elevational view of the portable electric circular saw in accordance with our new design;

FIG. 5 is a top plan view of the portable electric circular saw in accordance with our new design;

FIG. 6 is a bottom plan view of the portable electric circular saw in accordance with our new design;

FIG. 7 is a right side elevational view of the portable electric circular saw in accordance with our new design;

FIG. 8 is a left side elevational view of the portable electric circular saw in accordance with our new design; and,

FIG. 9 is a top, front and right side perspective view of a portable electric circular saw in accordance with our new design illustrating a state in which a battery is attached to the portable electric circular saw.

The broken line showing of environment in FIGS. 1-9 is for illustrative purposes only and forms no part of the claimed design.
